CLAIM

The ornamental design for a tool for truck and bus drivers, as shown and described.

DESCRIPTION

FIG. 1 is a perspective view of a tool for truck and bus drivers showing my new design;

FIG. 2 is a top view thereof;

FIG. 3 is a bottom view thereof;

FIG. 4 is a front elevational view thereof;

FIG. 5 is a rear elevational view thereof;

FIG. 6 is a right side elevational view thereof; and,

FIG. 7 is a left side elevational view thereof.

The bottom portion of the tool is broken to indicate an indeterminate length.
